CLAIM

The ornamental design for a wall plate, as shown and described.

DESCRIPTION

© General Electric Company 1976. The drawings of this patent document contain material to which a claim of copyright is made. The copyright owner, assignee herein, has no objection to the duplication of the patent drawing, but reserves all other copyright rights whatsoever. A certified copy of the certificate of copyright registration as registered by the U.S. Copyright Office is in the file of the application of this patent.

FIG. 1 is a front elevational view of a wall plate for a switch illustrating my new design.

FIG. 2 is a rear elevational view of the wall plate of FIG. 1.

FIG. 3 is a top plan view of the wall plate of FIG. 1 taken from the top end.

FIG. 4 is a bottom plan view of the wall plate of FIG. 1 taken from the bottom of the plate.

FIG. 5 is a side elevational view of the wall plate as in FIG. 1.

FIG. 6 is a horizontal sectional view of the wall plate of FIG. 1 taken along the line 6—6 of FIG. 1.

FIG. 7 is a vertical sectional view of the wall plate of FIG. 1 taken along the line 7—7 of FIG. 1.

FIG. 8 is a front elevational view of a wall plate for a wall receptacle illustrating my new design.

FIG. 9 is a front elevational view of a wall plate for two side-by-side switches illustrating my new design, the surface decoration being shown only in patches for clarity of illustration.
